(57) **CLAIM**

The ornamental design for a display screen with graphical user interface, as shown and described.

DESCRIPTION

FIG. 1 shows a front view of a display screen with graphical user interface showing the new design;

FIG. 2 shows another embodiment thereof; and,

FIG. 3 shows another embodiment thereof.

The broken line showing a display screen with graphical user interface is included for the purpose of showing portions of the article that form no part of the claim. The other broken lines in the figures show portions of the graphical user interface that form no part of the claimed design.

The polka dot patterns show portions of the graphical user interface and form no part of the claimed design.

1 Claim, 2 Drawing Sheets
